4 Claims. (Cl. 128—145.7)

The present invention relates to ventilation machines and particularly to portable ventilation machines by means of which oxygen can be supplied through a breathing mask to a patient.

It is known for workmen engaged in cleaning out tanks or other containers for fuels or other substances giving off fumes or vapour which is unable to support respiration or is otherwise harmful, to be trapped by pockets of the vapour or fumes and be rendered unconscious before they are able to don a breathing mask or like apparatus. Miners in coal and other mines are exposed to like dangers. Known ventilation machines are of no use in such circumstances in that they are not portable or have a plurality of independently adjustable controls requiring the use of a skilled operator before the machine is able to supply gas of the required tidal volume and cycling rate to a patient connected to the machine. Thus the use of such machines in a fuel tank or other surroundings, as described above, is undesirable.

Accordingly the present invention aims at providing a portable ventilation machine which automatically cycles gas at a preset tidal volume and cycling rate when externally supplied with gas, and which has no externally adjustable controls.

Accordingly the present invention provides a ventilation machine designed to be supplied with gas at a preset minute volume and to supply it to a patient at a preset tidal volume and cycling rate, and incorporating means to supply gas to the patient regardless of the position of the machine in its operating cycle when the patient applies negative pressure to the outlet of the machine.

By "negative pressure" throughout this specification is meant a sub-atmospheric pressure such as is applied when a patient attempts to inhale gas issuing from the outlet of the machine at a rate faster than the machine is supplying gas to the outlet.

In a modification of the present invention the machine incorporates a signalling device, such as a whistle, connected through a biassed one-way or blow-off valve to the machine so that when a respiratory obstruction occurs at the outlet of the machine, gas pressure in the machine rises to such a value that the one-way valve opens and causes the gas pressure itself to operate the signalling device. The signalling device thus enables malfunctioning of the machine or a condition of the patient requiring treatment, to be signalled.

The machine of the present invention may be self-contained, being connected to a replaceable and portable reservoir or cylinder of gas under pressure, this being carried on or by the body of the machine, or the machine may be designed to be connected to a supply line for gas at high pressure.

The drawing consists of a partially diagrammatic figure of the machine according to the present invention.

The machine includes a housing 10 for bellows 12 having flexible walls 14 and an end plate 16. The end of the bellows opposite to the end plate 16 is fixed to any convenient structural member 18 of the machine. A pivoted lever 20 is secured to the end plate 16, and this lever is urged about its fulcrum 22 by resilient means such as a compression spring 24 in a direction tending to reduce the

2

volume of the bellows 12. The machine has a supply line 26 for gas at high pressure, e.g. 60 lbs. p.s.i.; gas from the line 26 passes through a pressure reduction valve 28 and a preset needle valve 30. In the pressure reduction valve 28 the gas pressure is reduced, for example, to 5 lbs. p.s.i. and the needle valve 30 is adjusted and preset to give a desired minute volume, e.g. 10 litres per minute.

Gas leaves the bellows 12 through an outlet valve 32 operated by an over-centre mechanism 34 connected to the lever 20. The over-centre mechanism 34 comprises a lever 36 pivotally mounted on a support 37 attached to the structural member 18. The lever 36 is connected to the valve member 38 of the valve 32 and to a lever 40 by a tension spring 42. The lever 40 is pivoted on a support 44 secured to member 18, and its end opposite to that connected to the spring 42 is pivotally connected to a link 46 whose other end is connected to the biassed and pivoted lever 20. The link 46 has a longitudinal slot 47 of predetermined length, and the lever 20 has a pin 47a which projects into this slot and transmits motion of the lever 20 to the link 46 when the pin 47a reaches the upper or lower end (as seen in the drawing) of the slot according to whether the lever 20 is moving anticlockwise or clockwise. This arrangement thus constitutes a lost-motion connection between link 46 and lever 20. The operation of the over-centre mechanism is as follows. When the volume of the bellows is fairly large and the parts 20, 46, 42, 36, and 38 are as shown in the drawing, the force of spring 42 acts in a direction tending to keep lever 36 in its extreme anti-clockwise position and the valve 32 therefore open. When the bellows contracts the lever 20 moves clockwise as seen in the drawing, and when the pin 47a reaches the lower end of the slot 47, the movement is transmitted to link 46 and the right hand end of the lever 40 moves upwardly as seen in the drawing. Eventually this pivoting of lever 36 results in the toggle linkage comprising lever 40, spring 42, and lever 36 passing its dead-centre or in-line position with the result that the force of spring 42 acts in a direction tending to urge lever 36 towards its extreme clockwise position. This snap or toggle action results in valve 32 being closed. The continually occurring inflow of gas via pressure reducing valve 28 and needle valve 30 then causes expansion of the bellows 12, and lever 20 consequently starts to move anticlockwise. The pin 47a therefore moves towards and into engagement with the upper end of the slot 47, as seen in the drawing, and the link 46 is then moved upwardly by continued expansion of the bellows 12. This pivots lever 40 in a clockwise direction past the toggle in-line position and snaps valve 32 open again. It will thus be seen that the over-centre mechanism 34 and associated parts function as automatic means which automatically and repeatedly carries out the cycle of opening valve 32 at a predetermined maximum volume of the bellows 12 to allow the bellows to expel gas to the patient and closing valve 32 at a predetermined smaller volume of the bellows to allow the bellows to be recharged and the patient to exhale. Further means to be described effect automatic actuation of an expiratory or exhaling valve 60 in sympathy with valve 32.

From the outlet valve 32 the gas passes along a tube to a second preset needle valve 48, and along a tube 51 to an outlet 50 designed to be connected to the input limb 52 of a conventional breathing mask 54, of which the output limb 56 is connected to a union 58. The latter is connected to the expiratory valve 60 forming part of the machine. The expiratory valve 60 is of the biassed diaphragm type controlled by gas pressure and is connected to the output side of the outlet valve 32 of the bellows. The valve 60 has a diaphragm 62 bounding a space 64 and connected to a valve member 66 which can close

off the expiration outlet. The valve 60 also has conventional non-return valve including a ball 67 to prevent inhalation of the ambient atmosphere through the exhalation valve 60. The diaphragm 62 is biased by a spring 68 so that when gas is passing through the outlet valve 32 the expiration valve 60 is closed, the expiration valve 60 being opened when the pressure behind the diaphragm, i.e. in the space 64, is less than the outlet pressure of the bellows. Connected intermediate the second needle valve 48 and the tube 51 to the patient's breathing mask 54 is a blow-off valve 70 connected to a signaling device 73 such as a whistle. In this example of ventilation machine the bellows 12 are designed to be filled with gas at a pressure of 90 cms. of water, the expiration valve 60 to open at a differential pressure of less than or equal to 60 cms. of water, and the blow-off valve 70 to open at a differential pressure of 30 cms. of water.

Connected between the input to the blow-off valve 70 and the interior of the bellows 12 is a valve 72 connected to a biased diaphragm 74 having one side exposed to atmospheric pressure. The diaphragm valve 72 is biased shut by spring 76 when the pressure on the other side of the diaphragm is equal to or greater than atmospheric pressure. However when the pressure on said other side of the diaphragm becomes negative, as defined above, which happens by virtue of the connection between the diaphragm valve 72 and the outlet tube 51 to the patient, the diaphragm valve 72 opens to permit gas to be expelled from the bellows 12 directly to the patient under the action of the bias spring 24 of the bellows 12. Thus the diaphragm valve 72 acts as a spontaneous demand valve which is operated whenever the patient attempts to inhale.

Connected intermediate the pressure reduction valve 28 and the first needle valve 30 is a passageway 78 leading to a lift valve 80 communicating with the interior of the bellows 12. The plate 16 of the bellows 12 is arranged to contact a movable member 82 of the lift valve 80 so that when the bellows deflate further than the normal minimum volume at which the outlet valve closes by action of the over-centre mechanism, the lift valve is opened against its biasing spring 84. When this happens gas passing through the pressure reduction valve 28 passes directly to the interior of the bellows 12, thus by-passing the first needle valve 30.

The pressure reduction valve 28 can be of any convenient known construction, and since the precise details of such a valve form no part of the novelty of the present invention, the valve will not be described. The needle valves 30 and 48 can take any form which will give a reasonably constant rate of flow for a given substantially fixed input pressure, and a convenient construction has been found to be a block of metal with a small cylindrical hole drilled therethrough. Again, however, the precise construction of such flow regulators forms no part of the invention.

The operation of the machine is as follows:

Gas, such as oxygen, passes at high pressure to the pressure reduction valve 28 and issues therefrom at a pressure of about 5 lbs. p.s.i. From the pressure reduction valve 28 the gas passes through the first needle valve 30 to the interior of the bellows 12 at a minute volume determined accurately by the setting of the first needle valve 30. When the pressure of gas in the bellows reaches and exceeds the pressure corresponding to the bias on the lever of the bellows, e.g. 90 lbs. p.s.i., the bellows inflate, it being assumed that at this stage of the cycle the bellows are at or near their normal minimum volume position with the outlet valve 32 closed. When a volume of gas corresponding to a preset tidal volume, e.g. 500 mls., has entered the bellows the over-centre mechanism operates to open the bellows outlet valve. Gas is immediately supplied to the inlet side of the second needle valve 48 and to space 64 of the expiratory valve 60. The action of the second needle valve is to control the rate at which

gas flows from the bellows 12 to the patient, who is unable to breathe out because the expiratory valve 60 is closed.

The inspiration phase of the breathing cycle is brought to an end when the bellows reach their normal minimum position, at which the outlet valve 32 closes and the lift-off valve 80 is not operated. As soon as the outlet valve closes the pressure on the inlet side of the second needle valve 48 and in the control space 64 of the expiratory valve drops to enable the expiratory valve to open. The patient then exhales. While the patient is so doing the bellows 12 are again being filled by the constant supply of gas passing from supply line 26 to the bellows 12.

As soon as the patient attempts to inhale, at a time when the bellows outlet valve 32 is closed, negative pressure is applied to one side of the diaphragm valve 72 to cause that valve to open. Thus gas already in the bellows passes directly from the bellows to the patient via tube 51. Should the patient wish to inhale more gas than is immediately available in the bellows the bellows descend through their normal minimum volume position to a position in which the lift-off valve 80 is opened. Thereafter, until the lift-off valve is again closed, gas passes directly via the outlet of the pressure reduction valve 28, the lift-off valve 80, the bellows 12 and the diaphragm valve 72 to the patient. As soon as the patient stops breathing in, the diaphragm valve 72 closes and the bellows 12 start to inflate, thereby closing the lift-off valve 80 and re-establishing the automatic cycling of the machine.

Should the patient's respiratory needs be smaller than those which the machine is adjusted to supply, as when a blockage occurs in the patient's lungs, the pressure on the outlet side of the second needle valve 48, when the bellows output valve 32 is open, rises to the value of 30 cms. of water at which the blow-off valve 70 opens, gas passing therethrough to a whistle or other signal device 73 to draw the attention of an attendant to the fact that the patient needs special attention.

In order to ensure that the patient is supplied with gas passing through the machine and not with gas drawn from the surrounding atmosphere, the expiratory valve incorporates a non-return valve 67 so that when the patient attempts to inhale he has to draw in his gas from the outlet 50 of the machine and not be reversing the direction of gas flow through the expiratory valve 60.

Thus it will be seen that the present invention provides an open-circuit ventilation machine having a valuable dual facility coupled with substantially fully automatic operation and no need for external adjustment. Firstly the machine is adapted to supply gas at a minute volume and a tidal volume sufficient to ventilate normally an adult of average body weight, providing the machine is supplied, to the pipe 26, with the appropriate gas; and secondly the machine can respond automatically to spontaneous attempts to breathe by the patient connected to the machine. The patient so attempting to breathe is freely supplied with fully sufficient quantities of gas by virtue of the by-passing of flow regulator 30 through valve 80, and under these circumstances the automatic operation of the bellows 12 is over-ridden.

I claim:

1. A ventilation machine for supplying gas to a user comprising: a variable volume bellows; gas supply means comprising a pressure reducing valve having an output port in series with a flow regulator for feeding gas at a preset pressure and volume rate to the bellows; a first outlet valve for the bellows; an overcenter mechanism arranged to open the outlet valve when the volume of the bellows exceeds a first predetermined value and to close the outlet valve when the volume of the bellows falls below a second predetermined value; a tube connecting the outlet valve to a breathing mask for the user; a fluid pressure responsive valve constituting a second outlet valve for the bellows and located in a path for gas that is in parallel with at least a portion of the said tube

and connected thereto, means opening said second outlet valve when the pressure applied by the user to the second outlet valve is a negative pressure; and a further valve which constitutes an inlet valve for the bellows and is connected to the gas supply means between the output port of the pressure reducing valve and the said flow regulator, means responsive to a contraction of the bellows beyond the said second predetermined value consequent upon the application of said negative pressure by the user of the machine, for opening said last named inlet valve.

2. A machine according to claim 1 comprising an expiratory valve having a pressure-operated valve member responsive to the pressure in a control space of the expiratory valve, and comprising conduit means arranged to place the said control space in communication with the 15 interior of the bellows.

3. A machine according to claim 1 comprising a blow-off valve connected to the said tube, and a signalling device in series with said blow-off valve, whereby in operation a use in pressure due to obstruction of the patient's 20 breathing opens the blow-off valve and actuates the signalling device.

4. A ventilation machine for supplying gas to a user comprising: a variable volume bellows; gas supply means comprising a pressure reducing valve having an output 25 port in series with a flow regulator for feeding gas at a preset pressure and volume rate to the bellows; a first outlet valve for the bellows; an overcenter mechanism arranged to open the outlet valve when the volume of the bellows exceeds a first predetermined value and to close 30

the outlet valve when the volume of the bellows falls below a second predetermined value thereby in operation instituting a cyclic expansion and contraction of the bellows; a fluid pressure responsive valve constituting a second outlet valve for the bellows, a tube connecting said second outlet valve to a mask for the user and means opening said second outlet valve when the pressure applied by the user in said tube is a negative pressure, the opening of the said second outlet valve acting to interrupt the said cyclic operation of the bellows to allow the user to inhale.
